CLAIM

The ornamental design for a lamp for helmets, as shown and described.

DESCRIPTION

FIG. 1 is a perspective view of a lamp for helmets showing my new design;

FIG. 2 is a front view thereof;

FIG. 3 is a back view thereof;

FIG. 4 is a top view thereof;

FIG. 5 is a bottom view thereof;

FIG. 6 is a right view thereof; and,

FIG. 7 is a left view thereof.

The broken lines show portions of the article which form no part of the claimed design.
